UNITED STATES PATENT OFFICE.

MICHAEL KAMINSKY, OF NEW BRITAIN, CONNECTICUT.

SWITCH-OPERATING MECHANISM.

Application filed February 28, 1928. Serial No. 257,677.

This invention relates to switch-operating devices, and more particularly to a pedal-operated switch mechanism for controlling an electric motor-driven machine.

5 The objects of this invention are to provide a device of this nature which will be simple in construction, inexpensive to manufacture, easy to install and manipulate, compact, ornamental in appearance, and very 10 efficient and durable in use.

With these and other objects in view there has been illustrated on the accompanying drawings one form in which the invention may be conveniently embodied in practice.

15 Fig. 1 represents a front view of the switch-operating device.

Fig. 2 is a side view of the same showing the mechanism for attachment to the switch casing.

20 Fig. 3 is a rear view of a motor-driven sewing machine showing the invention installed in operating position.

Referring now to the drawings in which like reference numerals denote corresponding parts throughout the several views, the numeral 10 indicates a switch casing which is preferably substantially rectangular in shape and is provided with a pair of rearwardly-extending bolts 11 and 12 adapted to be passed 25 through the frame 13 of a sewing machine and to be secured to said frame, as by a plate member 14 and a pair of nuts 15, as clearly shown in Fig. 2. The switch is connected with the motor 42 by a pair of conductors 16 leading into the side of the casing 10, and said switch is actuated by a swinging arm or lever 30 17.

In order to support the operating mechanism upon the switch casing 10, provision is 40 made of a fixed vertical plate 18 having apertures for receiving screws 19 and 20 which are adapted to be driven into said casing. The plate 18 is provided at its opposite vertical sides with forwardly and inwardly bent 45 flanges 21 and 22 which serve as guides for a movable plate 23. The upper end of said plate 18 has a forwardly extending lug 24 having an aperture 24a for receiving the upper end of a spiral spring 25.

50 The fixed plate 18 is provided at its center with a rectangular aperture 26 for permitting the switch-actuating lever 17 to swing freely. The sliding plate 23 is rectangular in shape and is provided at its central portion with a pair of struck-out forwardly-extending curved clamping jaws 27 and 28

which are adapted to resiliently engage the upper and lower sides of the lever 17. The sliding plate 23 is also provided at its upper and lower ends respectively with forwardly 60 bent curled hooks 29 and 30, the hook 29 being adapted to hold one end of the spiral spring 25, while the hook 30 serves to hold a downwardly depending triangular loop member 31.

65 In order to form a resilient and adjustable connection between the loop member 31 and a control pedal 32 located under the sewing machine, provision is made of a helical resilient spring 33, preferably made somewhat stronger than the spring 25, being connected at its upper end to the loop member 31 and at its lower end to an eye bolt 34, screwed into the upper end of a turn buckle 35. The lower end of the turn buckle 35 is provided with a 70 second eye bolt 36, the threads of which are of opposite pitch from those of the eye bolt 34. The lower eye bolt 36 is connected in any suitable manner, as by a wire member 37 to a U-shaped clamping member 38 which is 75 adapted to surround a rearwardly extending rod 39 on the pedal 32. The clamping member 38 is securely held upon said rod 39 by a bolt 40 and a nut 41. A lock nut 43 is located on the lower eye bolt 36 for holding 80 the turn buckle 35 from twisting out of adjusted position.

85 In operation, when it is desired to close the switch for starting the motor, it will only be necessary for the operator to press down upon 90 the pedal 32 with his foot, whereupon the wire 37, the adjustable turn buckle 35, the resilient spring 33, and the triangular loop 31 will be pulled downwardly, causing the plate 23 to slide downwardly upon the fixed 95 plate 18 within the guide flanges 21 and 22. This will cause the switch lever 17 to move downwardly and close the switch of the motor 42.

100 It will be understood that the operator will hold the pedal 32 down as long as he desires to operate the machine, and that when he wishes to stop the machine, he will release said pedal, whereupon the spring 25 will return the lever 17 upwardly and open the 105 switch.

110 While there has been disclosed in this specification one form in which the invention may be embodied, it is to be understood that this form is shown for the purpose of illustration only, and that the invention is not to be limited to the specific disclosure but may be mod-

ified and embodied in various other forms without departing from its spirit. In short, the invention includes all the modifications and embodiments coming within the scope of 5 the following claims.

Having thus fully described the invention, what is claimed as new, and for which it is desired to secure Letters Patent, is:

1. In an attachment for a motor-operated 10 machine, a switch casing, a switch mounted in said casing, a switch-actuating lever projecting out of said casing, a fixed plate secured to said casing and having an aperture surrounding said lever, a movable plate slid- 15 able on said fixed plate and having a pair of lever-clamping lugs struck up from the inte-

rior thereof, and a pedal connected to said movable plate for closing said switch.

2. In an attachment for a motor-operated 20 machine, a switch casing, a switch mounted in said casing, a switch-actuating lever projecting out of said casing, a fixed plate secured to said casing and having an aperture surrounding said lever, a movable plate slidable on said fixed plate and having a pair of lever- 25 clamping lugs struck up from the interior thereof, and a pedal resiliently connected to said movable plate for closing said switch.

In testimony whereof, I have affixed my signature to this specification.

MICHAEL KAMINSKY.
